UNITED STATES PATENT OFFICE.

JOHN J. TOWER, OF MONTCLAIR, NEW JERSEY.

DESIGN FOR A TOOL-HANDLE.

No. 37,923.

Specification for Design.

Patented March 27, 1906.

Application filed November 16, 1904. Serial No. 233,051. Term of patent 14 years.

To all whom it may concern:

Be it known that I, JOHN J. TOWER, a citizen of the United States, residing at Montclair, in the county of Essex and State of New Jersey, have invented a new, original, and ornamental Design for Tool-Handles, as shown in the accompanying drawings.

Figure 1 is a plan view, and Fig. 2 an end view, of a tool-handle, showing my new design.

I claim—

An ornamental design for a tool-handle as herein shown.

JOHN J. TOWER.
